UNITED STATES PATENT OFFICE.

FRANK G. JOHNSON, OF BROOKLYN, AND JOHN H. HAYWARD, OF NORTHFIELD, NEW YORK.

ARM FOR FOLDING STEAMER-CHAIRS.

SPECIFICATION forming part of Letters Patent No. 271,248, dated January 30, 1883.

Application filed October 13, 1881. (No model.)

To all whom it may concern:

Be it known that we, FRANK G. JOHNSON and JOHN H. HAYWARD, citizens of the United States, residing respectively in the city of Brooklyn, in the county of Kings and State of New York, and at Northfield, in the county of Richmond and said State of New York, have invented new and useful Improvements in Arms for Folding Steamer-Chairs, of which the following is a specification.

The object of our invention is to increase the comfort and convenience of travelers upon ocean, river, and other steamers, which we accomplish by providing such arms for folding steamer-chairs as can be attached, detached, and extended and rotated in such a manner that they may be employed not only as arms proper, but as tables for various uses, as for writing, reading, lunching, card-playing, &c.

The peculiarities of our invention relate, first, to the manner of attaching and securing the arms to the chair, whereby they can be instantly detached therefrom whenever the chair is to be closely folded for packing it away; second, to their construction in such a manner that they can be rotated and held in a horizontal position for the purposes above enumerated; and, third, so they can be adjusted backward and forth horizontally, that they may be placed in the most favorable position when employed as tables.

The following is a full, clear, and exact description of the construction and operation of our invention, reference being had to the accompanying drawings, in which Figure 1 represents a side view of one of the arms placed in the ordinary vertical position; Fig. 2, a front view with the arms in a vertical position; Fig. 3, a vertical section through the line $\alpha\alpha$ of Fig. 1; and Fig. 4, a downward view with the table part of the arms placed in a horizontal position, one being turned outward and the other inward.

The method of constructing the arms and attaching them to and detaching them from the chair is thus described: A is a continuous frame, being made wider on the top than in its other parts to furnish more bearing-surface for the arm of the occupant of the chair, as seen in Figs. 2 and 3. Extending across and fast-

ened to this frame A is cane-work *a*, Figs. 1 and 3, or other suitable material. The object of placing this cane-work *a* in the central line of the frame A is to furnish a rim or guard to prevent articles which may be placed thereon from sliding off when the revolving part of the arm is employed as a table. This frame A, which we will term the "table-frame," is fastened to the base or carrying piece, E, by means of the metallic brackets C and D, Fig. 1. The lower ends of these brackets are fastened to the carrying piece E by means of screws. (Shown in Fig. 1.) The bracket C supports the front end of the table-frame A, to which it is secured by a pin, *c'*, which passes through and revolves in the bracket C. The bracket D supports the back end of the table-frame A, to which it is secured by a clamp bolt and nut, *d'''*. The pin *c'* and clamp-bolt *d'''* stand in line with each other, upon which rotates the table-frame A. The table A is held in any desired position, vertical or horizontal, by means of the ratchet or notched coupling *d'* *d''*, one half of which, *d'*, is secured to the table-frame A and the other half, *d''*, to the top of the bracket D.

Whenever it is desired to turn the rotating part of the arm A from a vertical to a horizontal position, or vice versa, it is only necessary to turn the clamping-nut *d'''* back far enough to allow the ratchet-coupling *d'* *d''* to work upon itself. The table A is then held in position by again tightening up the ratchet-coupling with the clamp-nut *d'''*.

The two tables A A, as shown in Fig. 4, can be turned into a horizontal position either way—that is, so the widest part of the arms will stand outward or inward from their centers of motion.

The carrying-piece E is placed upon and fastened to the side bar, H, Figs. 1 and 3, of the seat of the chair in the following manner: The carrying-piece E, which in shape corresponds with the side bar, H, of the seat, has a long slot, F, faced with metal around its edges. The back end of this slot is enlarged into a round opening, as shown in Fig. 1, to allow it (the carrying-piece E) to pass over the clamping-nut *g*. This clamping-nut *g* works on a threaded post fastened into the side bar, H, of the seat.

To place the carrying-piece E upon the side bar of the seat it is only necessary to pass the enlarged opening of the slot F over the clamp-nut g and slide it (the carrying-piece E) back 5 and tighten up the clamp-nut g, which binds the piece E to the side bar, H, of the seat.

As an additional security to keep the carrying-piece E in position, there is provided on the outside of the side bar, H, a wood or metallic 10 rib. (Shown in Fig. 1 by the dotted lines e e, and the end of which is shown at e in Fig. 3.) Corresponding to this rib e e is a groove cut in the carrying-piece E, which fits and works upon the rib.

When it is desired to move the entire arm forward to give the occupant of the chair more room behind the tables, when they are placed horizontally for use, it is only necessary to ease 15 the clamp-nut g and slide the carrying-piece E as far forward as required, and then tighten up the nut g. By thus sliding the pieces E E as far forward as the slots F F will permit, the tables A A can both be turned horizontally, with the wider part inward, thus forming a 20 double table in front of the occupant of the chair.

Either or both of the tables can be turned with the wider part outward, whatever be the 25 position of the carrying-pieces E E, and thus provide tables at the side of the occupant of the chair.

When it is desired to wholly remove the entire arms from the chair for whatsoever pur-

pose, it is only necessary to ease the clamp-nut g and then slide the carrying-pieces E E forward until the clamp-nut passes through the enlarged openings of the slots F F.

We are aware that adjustable and detachable arms and book-rests of chairs are not new. Therefore we do not claim broadly an adjustable or detachable arm to a chair; but

What we do claim as new, and desire to secure by Letters Patent, is—

1. In a folding chair consisting of an X-frame, the sliding piece E, having the slot F, 45 with an enlarged opening at the back end of the same, in combination with a table and the side rail, H, of the seat of the chair, having the rib e e, substantially in the manner and for the purposes described.

2. In a folding chair consisting of an X-frame, the rotating tables A A, mounted upon and in combination with the adjustable carrying-pieces E E and the brackets C D, substantially as and for the purposes set forth.

3. In a folding chair consisting of an X-frame, the combination of the carrying-piece E, having the slot F, with an enlarged opening at the back end of the same, the clamp-nut g, the rotating table A, brackets C D, and 60 ratchet-clamp d' d'', and clamp-nut d'''.
